Patented Oct. 25, 1921.

L. Hersh

INVENTOR

BY *Victor J. Evans* ATTORNEY

ATTORNEY

UNITED STATES PATENT OFFICE.

LEWIS HERSH, OF IRONWOOD, MICHIGAN.

SWITCH-STAND.

1,395,184.

Specification of Letters Patent. Patented Oct. 25, 1921.

Application filed July 10, 1920, Serial No. 395,286. Renewed August 12, 1921. Serial No. 491,874.

To all whom it may concern:

Be it known that I, LEWIS HERSH, a citizen of the United States, residing at Ironwood, in the county of Gogebic and State of Michigan, have invented new and useful Improvements in Switch-Stands, of which the following is a specification.

This invention relates to a switch operating mechanism and more particularly to that 10 part of the mechanism for giving motion to the switch operating rod and has for its primary object the construction and association of parts whereby the switch will be locked in either of its two positions but capable of being unlocked and operated by the 15 foot of the operator.

An object of the invention is the novel manner of associating the parts so that when foot pressure is brought to bear upon 20 one part the other parts will coöperate to release the switch point and automatically move the same.

A feature of my invention is the novel manner of associating the releaser with the 25 shaft so that in the initial movement thereof the locking devices will be released and further movement will cause the switch point to move.

With these and other objects in view the 30 invention will be better understood from the following detailed description taken in connection with the accompanying drawing wherein:

Figure 1 is a front elevation of the apparatus.

Fig. 2 is a top plan view.

Remaining figures are detailed views.

Again referring to the drawing illustrating one construction of my invention the 40 numeral 1 designates a stand which may be secured to the road bed or railroad ties in any suitable manner. This stand rotatably supports a shaft 2 that is connected to the switch point in any suitable manner such 45 as by the forked arm B. This shaft has rigidly secured thereto a lever 3 extending at right angles to the shaft so that the end portions 4 and 5 thereof may effectively co-operate with the pair of catches 6 and 7. 50 These catches are weighted so as to automatically move toward the lever 3 so that the slot 8 in the catch may automatically engage and hold the shaft 2 in either of its two positions. Each catch is provided with

a cam surface 9 for the purpose now to be 55 described. Loosely mounted on the shaft is a releaser 10 having its end portions 11 and 12 so disposed as to be easily pressed by the foot of the operator. This releaser 10 is so constructed and associated with the 60 catches that in the initial movement of the releaser the cam surface of that catch that locks the shaft 2 will be engaged and released from the lever 3. After the catch is released further movement of the releaser 65 will bring about engagement between the lever and releaser so that the shaft 2 will be rotated for throwing the switch point. To complete the invention the shaft is provided with a crank arm 13 connected by 70 a link 14 to the signal shaft 15 to which is secured, in any suitable manner, a signal device.

From the foregoing description it will be seen that when the switch is to be operated 75 it is only necessary to bring the foot to bear upon the releaser, which, in its movement automatically releases the catch and turns the shaft 2.

It is, of course, to be understood that the 80 invention may be constructed in various other manners and the parts associated in different relations and, therefore I do not desire to be limited in any manner except as set forth in the claims hereunto appended. 85

Having thus described my invention what I claim is:

1. A switch operating mechanism comprising a shaft, means for locking the shaft in either of its two positions, a foot operated 90 means for releasing the shaft and simultaneously operating the same.

2. A switch operating mechanism comprising a shaft, catches for holding the shaft in its various positions, and a foot operated 95 device for releasing the catches and turning said shaft.

3. A switch operating mechanism comprising a shaft, catches for holding the shaft in its various positions, a foot operated device for releasing the catches and turning 100 said shaft, and a signal device having a connection with the shaft.

4. A switch operating mechanism comprising a shaft, a lever connected thereto, 105 catches arranged to engage said lever and holding the shaft in either of its positions, and a device mounted upon the shaft and

adapted, in its initial movement, to release the catches and in further movement to turn the shaft.

5. A switch operating mechanism comprising a shaft, a lever rigidly secured thereto, a pair of catches arranged to alternately engage the lever for holding the

shaft in either of its positions, and a releaser loosely mounted on the shaft and cooperating with the lever and catches in a 10 manner that the catches will be first released and then the shaft turned.

In testimony whereof I affix my signature.

LEWIS HERSH.
